CLAIM

The ornamental design for a spaceship projector lamp, as shown and described.

DESCRIPTION

FIG. 1 is a top view of a spaceship projector lamp showing my new design;

FIG. 2 is a left view thereof;

FIG. 3 is a right view thereof;

FIG. 4 is a bottom view thereof;

FIG. 5 is a rear view thereof;

FIG. 6 is a front view thereof;

FIG. 7 is a top perspective view thereof; and,

FIG. 8 is a bottom perspective view thereof.

The broken lines shown in the drawings illustrate portions of the article and form no part of the claimed design.
